Fig. 8

*Fig. 9*FIG. 1 is a perspective view of an air damper embodying my new design invention.

FIG. 2 is a front elevational view thereof on a reduced scale.

FIG. 3 is a rear elevational view thereof on a reduced scale.

FIG. 4 is a left side elevational view thereof on a reduced scale.

FIG. 5 is a bottom plan view thereof on a reduced scale, the damper being broken away for convenience of illustration.

FIG. 6 is a sectional view taken on line 6—6 of FIG. 2 on a greatly enlarged scale.

FIG. 7 is a view similar to FIG. 6 showing another embodiment of my design invention; and

FIG. 8 is a view similar to FIG. 6 showing a further embodiment of my design invention.

FIG. 9 is a perspective view similar to FIG. 1 with the right end cap removed.

The characteristic features of my design reside in the specific configuration of the louver structure.

I claim:

The ornamental design for an air damper, as shown and described.
